ABSTRACT OF THE DISCLOSURE

A method of recovering benzene and toluene from normally liquid hydrocarbon mixtures containing in excess of 50% of benzene and toluene, together with acyclic mono - olefins, acyclic diolefins, cyclo - paraffins, cyclic mono-olefins, cyclic diolefins, and in some cases, sulfur and nitrogen or oxygen compounds, including distilling the mixture to recover a fraction boiling in the benzene-toluene range, subjecting this fraction to a hydrogen treatment in the presence of a catalyst and under conditions to dehydrogenate acyclic diolefins and hydrogenate acyclic mono-olefins, polymerizing the hydrogenation product, if desired, distilling the polymer product to recover a fraction boiling in the benzene-toluene range, subjecting the benzene - toluene fraction to a hydrogen treatment in the presence of a catalyst and under conditions sufficient to convert non-aromatic cyclic compounds to aromatic compounds and crack other non-aromatic compounds of lower boiling point.

RELATED APPLICATIONS

This application is a division of our copending application Ser. No. 582,652, filed Sept. 28, 1966, now abandoned.

The present invention relates to the separation of aromatic hydrocarbons. In a more specific aspect, the present invention relates to the separation of normally liquid hydrocarbon mixtures containing at least about 50% by volume of aromatics. In a still more specific aspect, the present invention relates to the recovery of benzene and toluene from normally liquid hydrocarbon mixtures containing at least about 50% by volume of aromatics.

Normally liquid hydrocarbon mixtures containing in excess of about 50% of benzene and toluene are commercially available from a variety of sources. These mixtures contain, in addition to the benzene-toluene, acyclic mono-olefins, including, secondary and tertiary mono-olefins of normal and branch chain structure, acyclic diolefins, cyclo-paraffins, cyclic mono-olefins and cyclic diolefins. Many of these hydrocarbon mixtures will also contain varying percentages of sulfur and some of them will also contain nitrogen or oxygen compounds.

Processes for the production of aromatic-rich hydrocarbon mixtures include the pyrolysis or cracking of crude petroleum, or fractions thereof, containing at least two carbon atoms such as ethane, propane, propylene, butane, natural gasoline, light straight run gasoline, straight run naphtha, kerosene, light cycle oils produced in the cracking of gas oils to produce gasoline, straight run gas oil, etc. These processes are carried out with or without the aid of catalysts and in the presence or absence of steam. Generally, the reaction temperature is in the neighborhood of about 1350 to 1550° F. and the pressure may be from 0 to 50 p.s.i.g. or higher. Such pyrolysis operations are generally carried out primarily for the production of ethylene. The pyrolysis of hydrocarbons to produce ethylene results in a normally gaseous product

2

containing unsaturated hydrocarbons, including, ethylene; normally liquid hydrocarbons rich in unsaturated hydrocarbons, including, olefins and diolefins of varying boiling points and structures and various aromatic hydrocarbons; as well as tar. The normally liquid hydrocarbons and tar obtained from this process are considered by-products. These by-products are removed by rapidly cooling the pyrolysis products, usually by quenching with water, to a temperature of about 400° F. A viscous tarry material condenses out of the gas during the quenching operation. Gases from the quenching operation are then compressed and cooled and a liquid material boiling between about 100° and 360° F. condenses out of the gases during the compression-cooling operation. This last material is known as dipolene.

Dipolene fractions obtained in the manner set forth normally contain about two-thirds aromatics and one-third non-aromatics, the latter being mostly olefins and diolefins. In a typical situation dipolene will contain about 64% aromatics consisting essentially of benzene and toluene and about 36% non-aromatics including acyclic mono-olefins, including, secondary and tertiary mono-olefins of normal and branch chain type, acyclic diolefins, cyclo-paraffins, cyclic mono-olefins, cyclic diolefins, and, in some cases, oxygen compounds and sulfur compounds.

It has heretofore been suggested that the removal of aromatics from dipolene and other aromatic-containing mixtures can be accomplished by selective adsorption on solid materials, such as silica-gel, activated alumina, etc. However, such selective adsorption of aromatics is relatively ineffective since diolefins, present in the mixture, behave quite similarly to the aromatics. The other approach is, of course, the removal of the unsaturated compounds from the aromatics. Such removal of unsaturates has heretofore been practiced by a number of processing schemes, for example, hydration, halogenation, hydrohalogenation, carbonization, hydrogenation followed by glycol-water extraction, ozonolysis, polymerization, etc. However, because of the high concentrations of unsaturates in mixtures of aromatics, such as dipolene, processing costs and aromatic losses due to reactivity of the aromatic compounds has generally confined the prior art treatments, at least commercially, to hydrogenation and polymerization.

Under the conditions normally employed in the hydrogenation of aromatic-rich mixtures, such as dipolene, including, using a palladium catalyst for diolefin conversion followed by a second hydrogenation and finally the glycol-water extraction of the product, the cost of hydrogenation is usually quite high, since large quantities of hydrogen are necessary, and the glycol-water extraction alone is an expensive proposition. In addition, high pressures and high hydrogen to hydrocarbon ratios must be employed to produce an essentially olefin-free product. Under these conditions, diolefins normally undergo a Diels-Alder reaction to produce polymers, gums and resins. Further, when a palladium catalyst is used it is readily poisoned by feed mixtures having normal sulfur contents and hydrogen containing small amounts of free hydrogen sulfide.

Where polymerization is utilized for the separation of unsaturates from aromatic mixtures, typical polymerization conditions lead to undesirable losses of aromatics. This is caused by the alkylation of the aromatics, which takes place with approximately the same ease as the polymerization.

Another convenient source of aromatic hydrocarbons, particularly benzene and toluene is an aromatic light oil obtained by the high temperature carbonization of coal. The products of this carbonization are coke and the aromatic light oil. This light oil contains relatively high con-

centrations of unsaturates, sulfur and nitrogen compounds in addition to benzene, toluene and xylene. For example, a coal tar light oil boiling in the range of about 150-300° F. will contain, roughly, 86% benzene-toluene and about 14% unsaturates and impurities. The non-aromatics include acyclic mono-olefins, including, secondary and tertiary mono-olefins of normal and branch chain type, acyclic diolefins, cyclic paraffins, cyclic mono-olefins, cyclic diolefins and substantial amounts of sulfur and sulfur compounds as well as nitrogen compounds.

Heretofore, the recovery of aromatics from coal tar light oils, particularly the recovery of benzene, has been effected by acid washing with sulfuric acid, benzene crystallization followed by acid washing, hydrotreating followed by solvent extraction with an aromatic-selective solvent or hydrotreating followed by high severity hydrocracking. Each of these treatments has been found to have its own peculiar drawbacks. For example, acid treating alone results in a benzene product of high purity but having a high thiophene content. Benzene crystallization followed by acid washing will produce a product of high purity having a low thiophene content; but the recoveries of benzene are low. Hydrotreating followed by solvent extraction produces a high purity benzene product but is a costly process and coking problems in the preheater to the hydrotreater exist. The final technique, of hydrotreating followed by high severity hydrocracking, is a costly proposition because of the high pressures and high temperatures involved and at times such treatment does not produce specification grade benzene.

In accordance with the present invention it has been surprisingly discovered that olefins may be readily removed from liquid hydrocarbon mixtures containing, in excess of about 50% aromatics, by selectively distilling the mixture to recover a heart-cut rich in desired aromatics, selectively treating the heart-cut fraction to convert the acyclic diolefins and at least a portion of the acyclic mono-olefins, and, finally, selectively treating at least a portion of the product of the first selective treatment to convert the cyclic compounds to aromatics and any remaining non-aromatic compounds to compounds having

5

introduced to distillation column 112 where it is separated into three fractions. A heart-cut or benzene-toluene concentrate boiling between about 140 and 250° F., and, preferably between 160 and 245° F. is separated and discharged through line 114. A fraction boiling below about 140° F., and, preferably, below about 160° F. is discharged through line 116. Finally, materials boiling above about 250°, and, preferably, 245° F., are discharged through line 118. The benzene-toluene concentrate passing through line 114 is fed to a first polymerization zone 120. In polymerization zone 120 the benzene-toluene concentrate is polymerized under low severity polymerization conditions. Under such low severity conditions diolefins and tertiary mono-olefins undergo polymerization, with little or no alkylation of aromatics and only minor conversion of toluene. In polymerization unit 120 the material is subjected to a temperature of about 0 to 300° F. and, preferably, 100 to 200° F., at a pressure of 0 to 1000 p.s.i.g., and, preferably 50 to 200 p.s.i.g., and at a liquid hourly space velocity (LHSV) of about 0.1 to 10, and, preferably, 0.5 to 2. Any acidic, solid, oxide catalyst, such as, silica-alumina, boria-alumina, silica-magnesia, fluoride promoted alumina, etc., may be used. The product of polymerization unit 120 is discharged through line 120.

15 The advantages of processing a benzene-toluene concentrate in accordance with the present invention as opposed to a board boiling range aromatic mixture are illustrated by the examples in the table which follows. The feed material to Runs #1 and 2 was a raw dipole containing about 52.4% benzene and 11.6% toluene. By distilling the raw dipole to recover a benzene-toluene concentrate or heart-cut boiling from 160 to 245° F., the following feeds to the polymerization unit were obtained for Runs #3 to 5.

20

boiling points differing from the boiling range of the desired aromatics.

The details of the present invention can best be understood and exemplified by reference to the following description when read in conjunction with the drawings, wherein:

FIG. 1 is a flow diagram of one form of the present invention.

According to the present invention it has been found quite surprisingly, that the problems of recovering benzene and toluene from coal tar light oils can be overcome by a novel combination of low severity polymerization.

According to a specific technique, high purity aromatics are separated from aromatic feed mixtures by selective distillation followed by two states of low severity polymerization. The features of the technique will be more clearly understood by a specific example illustrated in the drawing.

In accordance with the drawing, a highly aromatic feed mixture is introduced to the system, from an external source not shown, through line 110. The feed mixture is

55 A comparison of the results obtained in the table immediately above shows the superiority of the polymerization of a benzene-toluene concentrate under the selective conditions of the present invention.

60 The product of polymerization reactor 120 still contains substantial amounts of unsaturates which are normally of the secondary mono-olefin-type having normal or branched chains. Further polymerization of these olefins could only be accomplished under severe conditions which would lead to aromatic alkylation and, thus, benzene-toluene depletion. This is true since processing secondary olefins over an acidic catalyst yields secondary carbonium ions which undergo polymerization or aromatic alkylation with equal facility. If, however, this product is further polymerized under mild conditions and in the presence of a tertiary olefin, from an external source, these difficulties are substantially overcome.

65 Accordingly, the polymer from line 122 is passed to distillation column 124 where it is fractionated to separate a higher boiling product boiling above about 250° F., and, preferably, above 245° F. This high boiling material is

discharged through line 126. The lower boiling portion of the polymerized material is discharged through line 128. From line 128, the low boiling fraction is charged to a second polymerization zone 210. This is accomplished by closing valve 212 in line 128 and opening valve 214 in line 216. It has been found in accordance with the present invention, that the second polymerization unit 210 can be operated under mild polymerization conditions to effect additional polymerization by introducing a tertiary olefin to polymerization unit 210, from an external source (not shown) through line 218. The tertiary olefin produces tertiary carbonium ions and shifts the driving force of the reaction toward polymerization as opposed to alkylation of aromatics. Suitable olefins for this purpose include C_4 to C_{10} olefins and their dimers, particularly isobutylene and isoamylene. The tertiary olefin may be utilized in ratios of about 1/1-1000 volumes of olefin per volume of feed, and, preferably, 1/10-100. The polymerization may be carried out at temperatures between about 0 and 300° F. and, preferably 50 to 200° F., at a pressure of about 0 to 1000 p.s.i.g., and, preferably, 50 to 200 p.s.i.g., and at a liquid hourly space velocity (LHSV) between 0.1 and 10, and, preferably, between 0.5 and 2. Suitable catalysts include any acidic, solid oxide catalysts, such as, silica-alumina, boria-alumina, silica-magnesia, fluoride promoted alumina, etc. Thus, essentially the same process is carried out in the second polymerizer as in the first with the exception of added olefin. The following table shows the results of polymerizing the product of Run #5 of the previous table, with and without the addition of tertiary olefins, as set forth herein.

TABLE II

Catalyst	Run		35
	$SiO_2-Al_2O_3$	$SiO_2-Al_2O_3$	
Temperature, ° F.	200	200	
Pressure, p.s.i.g.	100	100	
LHSV	1	1	
Isobutylene, percent by volume	0.0	1.0	40
Product (160-245° F.):			
Recovery, percent by volume	95	95	
<Benzene, percent by volume	8.6	5.6	
Benzene, percent by volume	77.0	79.6	
Toluene, percent by volume	15.0	15.0	
>Toluene, percent by volume	0.0	0	

The effects of the addition of tertiary olefin on the polymerization is evident from the above runs. Specifically, the addition of 1% by volume of isobutylene more than doubled the rate of disappearance of olefins through polymerization. By employing larger amounts one can obtain an essentially olefin-free product. The polymer from polymerization unit 210 is discharged through line 220. The polymer is then passed to distillation column 222 where materials boiling above about 250° F., and, preferably, above 245° F., are separated and discharged through line 224. The overhead from column 222 is discharged through line 226 and valve 228. It then passes

to line 134 and column 136, where materials boiling below about 176° F. benzene, and toluene are separated from the mixture and discharged through lines 138, 140 and 142, respectively. The benzene and/or toluene can be further purified by a conventional hot clay treatment by passing the same through line 144 and valve 146 or line 148 and valve 150, respectively, to clay treater 152. The benzene and toluene from treater 152 may be discharged through lines 154 and 156, respectively. Alternatively, benzene can be withdrawn in advance of the clay treater through line 158 and valve 160 and toluene through line 162 and valve 164. Since, the hydrocracked product normally contains less than about 5% by volume of undesirable products, the clay treater could be used ahead of column 136 to treat the entire hydrocracked product.

What is claimed is:

1. A method for recovering benzene and toluene from normally liquid hydrocarbon mixtures containing in excess of about fifty percent (50%) by volume of benzene and toluene comprising:
  - (a) distilling said mixture to remove a benzene-toluene concentrate boiling between about 140° to 250° F.;
  - (b) polymerizing the concentrate of (a) at a temperature of about 0 to about 300° F., and a pressure of about 0 to 1000 p.s.i.g. and in the presence of an acidic, solid oxide catalyst;
  - (c) distilling the product of (b) into a concentrate having a boiling point of about 140° to 250° F.;
  - (d) polymerizing the concentrate of (c) in the presence of a tertiary olefin from an external source at a temperature of about 0° to about 300° F., a pressure of about 0 to 1000 p.s.i.g. and in the presence of an acidic solid oxide catalyst; and
  - (e) distilling the product of (d) into a benzene and toluene fraction.
2. The method of claim 1 wherein the tertiary olefin of step (d) is a C_4 to C_{10} tertiary olefin.
